UNITED STATES PATENT OFFICE.

CONRAD FERRETTIE, OF MISHAWAKA, INDIANA, ASSIGNOR TO MISHAWAKA RUBBER AND WOOLEN MANUFACTURING COMPANY, OF MISHAWAKA, INDIANA, A CORPORATION OF INDIANA.

DESIGN FOR AN OVERSHOE.

Application filed September 3, 1926. Serial No. 18,966. Term of patent 14 years.

To all whom it may concern:

Be it known that I, CONRAD FERRETTIE, a citizen of the United States, residing in Mishawaka, county of St. Joseph, and State of Indiana, have invented a new, original, and ornamental Design for an Overshoe, of which the following is a specification, reference being had to the accompanying drawing, forming a part thereof.

Fig. 1 is a front perspective view of an overshoe showing my new design and Fig. 2 is a side view thereof.

I claim:

The ornamental design for an overshoe as shown.

CONRAD FERRETTIE.
